REFLECTOR MOUNTING

Lacey R. Blackman, Bridgeport, and Fred A. Nichols, Stratford, Conn.

Application February 28, 1938, Serial No. 193,128

6 Claims. (Cl. 88—82)

This invention relates to new and useful improvements in light reflectors and has particular relation to the mounting of such reflectors to form letters, numerals, signs, strips, etc.

5 The objects and advantages of the invention will become apparent from a consideration of the following detailed description taken in connection with the accompanying drawing wherein a satisfactory embodiment of the invention is 10 shown. However, it is to be understood that the invention is not limited to the details disclosed but includes all such variations and modifications as fall within the spirit of the invention and the scope of the appended claims.

15 In the drawing:

Fig. 1 is a plan view showing a metal strip having light reflectors mounted thereon in accordance with the invention;

20 Fig. 2 is an enlarged vertical sectional view through one of the reflectors and its mounting;

Fig. 3 is a plan view on an enlarged scale showing one of the reflectors and its mounting;

Fig. 4 is a plan view showing the use of the invention in the formation of a numeral;

25 Fig. 5 is a plan view showing the use of the invention in the formation of a letter; and

Fig. 6 is a plan view showing the use of the invention in the formation of a sign.

Referring in detail to the drawing and at first

30 more particularly to the Figs. 1 through 3 at 19 is shown a base or mounting member comprising a length of strip metal stock preferably aluminum or other non-corrosive or corrosion resisting metal. Base 10 is also preferably of a

35 soft material whereby it may be bent to conform to any of the various surfaces to which it may be desired that it be fastened. The length of the base will depend on the purpose for which it is to be used and use and price may also determine 40 the number and size of the reflectors attached to the base as will appear.

Secured to the base 10 are a plurality of like glass reflectors 11 each intermediate its length including a lateral bead 12 and each having its 45 lower end enclosed by a cup-like member 13 the upper portion of which is inturned to provide a flange 14 overlying the upper side of bead 12. As disclosed in Fig. 2 the lower end of the reflector is against the bottom wall of the member 50 13 although it will be apparent that there may be intervening means if desired.

The bottom walls of the cup-like members 13 are held against the upper side of the base 10 as such members are received in ring-like members 55 or parts 15 comprising holders and attaching

means for securing the reflectors to the base 10. Holders 15 are open through both ends and at their upper ends include inturned portions or flanges 16 overlying the inturned portions 14 of the members 13 whereby the latter and the reflectors 11 may not pass through the upper or outer ends of the holders. 5

Inclined side walls 17 of the holders connect their upper flanges 16 with outwardly directed lower flanges 18 which may be straight across 10 their under or inner surfaces as shown or may be curved when the base is to be applied to a curved surface. Flanges 18 each carry a plurality of attaching lugs 19 for securing the holders 15 to the base 10 and while in the drawing 15 each flange 18 is provided with four such lugs it will be understood that the number may be varied.

Base 10 is provided with openings 20 in such number and spaced relation as to accommodate 20 the lugs 19 on the holders 15. The arrangement is such that with the holders about the cup-like members 13 and the reflectors 11 as in Fig. 2 the lower ends of the holders are against the base and the lugs 19 of the holders are through the 25 openings 20 in the base. The ends or portions of the lugs at the lower or under side of the base are bent over or clinched whereby to prevent 30 casual movement of the holders.

The edges of the flanges 14 and 16 are substantially against the sides of the reflectors 11 whereby to exclude moisture and prevent tampering with such flanges in any attempt to remove the reflectors through the front of the 35 holders. The reflectors being mounted as shown and described the base may now be attached to any desired surface or object. The base 10 is of the desired length and shape or configuration and is provided with holes 21 for the passage of 40 screws or other fastening or securing means to be driven into the support on which the base and the reflectors are to be mounted.

Base 10 as well as the cup-like members 13 and particularly the base and the holders 15 are of bright non-tarnishing material whereby their 45 exposure to the weather will not result in their splitting, etc. They will not require continuous attention as painting or the like for their upkeep. The base being made or cut to the desired shape and size at the factory no particular 50 work is required at the place of application for the proper installation of the device. When it is in place the attaching lugs 19 are concealed and may not be pried up for the removal of the reflectors but when a reflector is broken the base 55

may be removed from its support and the lugs 19 of that reflector pried loose to permit of removal of holder 15 from the base and the replacement in the holder of an unbroken reflector.

5 Fig. 4 shows an arrangement wherein the base 22 is in the form of the numeral "2" and has applied thereto a plurality of the reflectors 11 secured by the holders 15. In Fig. 5 the reflectors are attached to a base 23 comprising the letter "A". Somewhat similarly in Fig. 6 the reflectors 11 are attached to a base 24 by means of the holders 15. The base 24 is in the form of an arrow although it will be appreciated that the invention is applicable to other designs or forms of signs. Each of the bases 22, 23 and 24 is provided with the desired number of holes 25 for the passage of screws or other securing means whereby the letters, numerals, signs, etc. may be attached to supports.

20 Having thus set forth the nature of our invention, what we claim is:

1. In a light reflecting device, a sheet metal base, a reflector unit wholly at the front side of said base and comprising an elongated lens and a 25 cup-like means secured to said lens and completely encompassing the inner end thereof, said cup-like means including a bottom wall and having an angular shoulder intermediate the ends of the lens, a tubular ring-like part wholly at said 30 front side of the base and enclosing said cup-like means, lugs on the inner end of said part and passing through the base and clinched at the rear side thereof whereby said part is attached to the base with its inner end against the front 35 of the base, and a flange on said part and engaging the angular shoulder of said cup-like means and securing it with its bottom wall against the front side of the base.

2. In a light reflecting device, a sheet metal 40 base, a lens having a radially extending shoulder and a forwardly projecting body portion substantially at right angles to said shoulder, a metal cup-like means enclosing the inner portion of said lens, said means including a bottom wall 45 and a flange spaced from said wall and overlying said shoulder and securing the lens to the means, a metal ring-like part about said means, lugs on the inner end of said part and passing through the base and clinched whereby the part is secured 50 to the base, and said part including a flange overlying the flange of the means and securing the latter with its bottom wall against the front side of the base.

3. In a light reflecting device, a flexible metal 55 base, a row of light reflecting units each comprising a lens and a cup-like means secured to and enclosing the inner end portion of the lens, said cup-like means including a bottom wall disposed against the base, a ring-like part encircling the 60 sides of the cup-like means, lugs on said part and passing through the base and clinched whereby to secure the part to the base with the inner end of the part against the base, and said part in-

cluding a flange overlying a portion of said cup-like means and securing it in position with its bottom wall against the base.

4. In a light reflecting device, a flexible metal 5 base adapted to be readily bent to conform to the surface of a support to which the base is to be attached, a row of light reflecting units mounted on said base, each of said units comprising a tubular metal housing open at each end and having one end against the said base, a lens supported by said housing and projecting through the outer end thereof, an outwardly extending annular radial flange on said housing at the inner end thereof and bearing against said base, said base having spaced perforations in its portions about the edges of said flange, lugs on said flange and passing through said perforations and clinched at the rear side of said base and securing the housing thereto, and said base imperforate in its portions within the bounds of said 10 housing and completely closing the inner end of the latter.

5. In a light reflecting device, an elongated flat 15 flexible sheet metal base, a plurality of lenses each having a radial shoulder and a forwardly 20 projecting body portion substantially at right angles to said shoulder and directed away from said base, a ring-like part encircling the inner portion of each of said lenses, lugs on the inner 25 ends of said parts and passing through said base and clinched whereby the parts are secured to the base, a continuous flange on each said part and overlying the shoulder of the lens encircled by said part and securing the lens to the base, said flange of each ring-like part having its edge 30 substantially against said forwardly projecting body portion of the lens encircled by said part, and each of said ring-like parts spaced from the next adjacent thereof to permit of deforming of 35 said flexible elongated base to have the latter 40 conform to the surface to which it is applied.

6. In a light reflecting device, an elongated flat 45 flexible sheet metal base, a plurality of lenses each having a radially extending shoulder and a forwardly projecting body portion substantially 50 at right angles to said shoulder, a plurality of cup-like means each enclosing the inner portion of one of said lenses, said means including a bottom wall and a flange spaced from said 55 wall and overlying said shoulder and securing the lens to the means, an independent metal ring-like 60 part encircling each of said lenses and means and secured to said base, each of said ring-like parts including a flange overlying the flange of the means it encircles whereby the latter is secured between the flange of the ring-like means and said elongated flexible base, and each of said ring-like parts spaced from the next adjacent thereof to permit of deforming of said flexible elongated base to have the latter conform 65 to the surface to which it is applied.

LACEY R. BLACKMAN.
